Inventor
James M. Edwards,

By his Attorney

M. C. Hyatt

UNITED STATES PATENT OFFICE.

JAMES M. EDWARDS, OF NEW YORK, N. Y.

VENTILATING DEVICE.

1,405,820.

Specification of Letters Patent. Patented Feb. 7, 1922.

Application filed September 20, 1920. Serial No. 411,496.

To all whom it may concern:

Be it known that I, JAMES M. EDWARDS, a citizen of the United States, and resident of the city of New York, in the county and 5 State of New York, have invented certain new and useful Improvements in Ventilating Devices, of which the following is a specification.

This invention relates to ventilating devices, and has for its primary object to provide inexpensive and effective means for regulating and equalizing the temperature of a room.

The present invention in one embodiment 15 thereof comprehends the provision of means adapted for association with a suitable heat supply device such as a gas or oil burner, or a radiator, the said device being provided with a separate inlet passage for relatively 20 cold air adjacent to the floor of the room, or from the exterior of the building, and also with means for thoroughly mixing the currents of cold and warm air and disseminating the same into the room adjacent to 25 the floor surface.

In general the invention contemplates the provision of a device for the above purpose which may be constructed at relatively small cost, will occupy a minimum of space, 30 and in the successful operation of which little or no additional expense will be involved.

With the above and other objects in view, the invention consists in the improved temperature equalizing or regulating device as 35 will be hereinafter more fully described, illustrated in the accompanying drawings, and subsequently incorporated in the subjoined claims.

40 In the drawings, wherein I have disclosed several desirable embodiments of the invention, and in which similar reference characters designate corresponding parts throughout the several views:

45 Figure 1 is a front elevation partly in section, illustrating one embodiment of my invention.

Figure 2 is a vertical transverse section showing the device arranged in operative 50 position with respect to a radiator.

Figure 3 is a section taken on the line 3—3 of Figure 2, and,

55 Figure 4 is a view similar to Figure 2 illustrating a slightly modified form of the device.

Referring in detail to the drawings, 5

designates a casing preferably constructed of sheet metal, and which may be of any desired size and dimensions. This casing is provided with front and rear walls 6 and 7 respectively, and an intermediate vertically disposed partition wall 8 extending between the opposite side walls of the casing. The front wall 6 is provided in its lower portion with the spaced openings 9 and 10 respectively, while the rear wall 7 terminates at its lower edge above and in spaced relation to the bottom wall of the casing to provide an outlet opening 11 extending across the entire width of the casing.

A relatively short vertically disposed transverse partition wall 12 extends between the front wall 6 and the partition wall 8 of the casing, and is located between the openings 9 and 10. The space above this transverse partition wall and between the front wall 6 and the wall 8 provides a mixing chamber 13.

The partition wall 8 at the rear side of the mixing chamber is provided with an opening 14. A fan 15 is mounted between the wall 8 and the rear wall of the casing in axial alignment with this opening. This fan may be operated by any suitable means, and may either be mechanically driven, or operated 85 automatically in such cases where a sufficiently strong current of heated or cold air is available for the purpose of driving said fan.

In the operation of the invention as above explained, a gas or oil burner may be arranged within or adjacent to the opening 9 in the front wall of the casing, as indicated in Figure 1, and the heated air rising above the partition 12 will draw cold air through the opening 9 from the floor surface of the room, and these hot and cold air currents are thoroughly mixed in the chamber 13 from which they pass through the opening 14 in the partition wall 8, and are driven downwardly by the fan 15 and through the outlet opening 11 at the rear side of the casing, where the heated air is distributed over the surface of the floor.

As is well known, in all apparatus now used for the heating of rooms or apartments 105 there is a relatively high temperature adjacent to the ceiling of the room, while at the floor surface the temperature is many degrees lower. Owing to the tendency of the heated air to rise from the radiator or other heating 110 apparatus, the occupant of the room often suffers actual discomfort owing to the fact

- that the air adjacent to the floor surface is practically unheated. By means of my present invention it will be seen that this deficiency in present heating apparatus is entirely overcome and the cold air adjacent to the floor is thoroughly mixed with the heated air current, and a column of air of equalized temperature is then discharged over the floor surface.
- 10 As shown in Figure 2, the invention may be employed in connection with the ordinary steam or hot water heating radiator which I have indicated at 16, and in such case the opening 8 in the front wall of the casing 5 is arranged closely adjacent to the radiator columns, while the other opening 9, constituting the cold air inlet, is exposed beyond the end of the radiator. Of course it is manifest that the device might be made in elongated form, 15 and hot air and cold air receiving openings of greater size provided.

In Figure 4 of the drawings I have indicated a slightly modified embodiment of the invention, wherein a pipe or conduit 17 is connected to the front side of the casing 5 in line with the opening 9. This pipe receives cold air exteriorly of the room, and is provided with a suitable regulating valve 18.

In the operation of this form of the device 30 the air is not drawn from the floor surface through the mixing chamber, but exterior cold air is mixed with the current of heated air from the radiator or other source of heat. This embodiment of the invention is desirable 35 where a very high degree of heat is available, so that a constant supply of heated fresh air instead of a partially vitiated air is constantly released into the room.

From the foregoing description considered 40 in connection with the accompanying drawings, the construction, manner of operation and several advantages of the invention will be fully understood. The device is exceedingly simple in its construction, and can, 45 therefore, be manufactured and sold at nominal cost. Owing to the fact that no special heating apparatus is necessary, the operating cost will be practically nil. It will be appreciated that a constantly equalized temperature of the air in a room or apartment may be maintained, and the air adjacent to the floor surface will always be substantially the same temperature as the air at higher elevations.

It will be seen that there is no permanent 50 connection of the device to the burner, radiator or other heating apparatus, so that it may be readily moved from one room to another.

In the above description and the accompanying drawings, I have described and illustrated several desirable and practical embodiments of the device, but it is, nevertheless, to be understood that the same is susceptible of a great many modifications in the

form, proportion and arrangement of its several parts, and I accordingly reserve the privilege of adopting all such legitimate changes and modifications as may be fairly embodied within the spirit and scope of the invention as claimed.

I claim:

1. A device of the character described comprising a casing having spaced openings in one wall thereof, and a central vertical partition extending between its side walls, 75 a transverse partition located between the openings and providing separate hot and cold air inlet passages, said partition terminating below the upper end of said vertical partition, the space above said transverse partition constituting a mixing chamber for the hot and cold air currents, the rear wall of the casing having an outlet opening at its lower end and a fan mounted within the casing to thoroughly mix the hot and cold air 80 currents and direct the same through said outlet opening.

2. A device of the character described comprising a casing having hot and cold air inlet openings in its front wall and adjacent to its base, partition walls within said casing forming separate hot and cold air passages and a mixing chamber; one of said partition walls having an opening therein, the rear wall of the casing being provided with an 90 outlet opening at its lower end, and a mixing fan mounted adjacent to said opening in the partition wall to thoroughly mix the hot and cold air currents and discharge the same through said outlet opening.

3. A portable ventilating device comprising a casing having means therein providing separate air inlet passages opening at one of their ends through one wall of the casing, said casing also having a mixing chamber 105 with which said passages communicate and an air outlet passage communicating with the mixing chamber and opening through another wall of the casing, the outlet passage having an area substantially equivalent to 110 the combined areas of the air inlet passages.

4. A portable ventilating device comprising a substantially rectangular casing having its interior divided by a plurality of partitions into separate hot and cold air inlet passages opening at one of their ends through one side wall of the casing at the lower end thereof, a mixing chamber with which the other ends of said passages communicate, and an air outlet passage opening through the opposite side wall of said casing at its lower end and extending across substantially the entire width of the casing 115 one of said partitions having an opening therein affording communication between 120 said outlet passage and the mixing chamber.

In testimony whereof I affix my signature.
JAMES M. EDWARDS.
